UNITED STATES PATENT OFFICE.

NILS FREDERICK AMBURSEN, OF BROOKLINE, MASSACHUSETTS.

CLOTHES-POUNDER.

1,089,809.

Specification of Letters Patent. Patented Mar. 10, 1914.

Application filed October 18, 1913. Serial No. 796,017.

To all whom it may concern:

Be it known that I, NILS FREDERICK AMBURSEN, a citizen of the United States, and a resident of Brookline, in the county of Norfolk and State of Massachusetts, have invented a new and useful Improvement in Clothes-Pounders, of which the following is a specification.

My invention relates to clothes pounders and its object is to improve the construction thereof in the manner hereinafter set forth.

One embodiment of my invention is illustrated in the drawings which accompany and form a part of this specification; but it will be understood that various modifications may be made in the particular device shown, without departing from the spirit of my invention.

In the drawings, Figure 1 is a vertical section of a clothes pounder embodying my invention. Fig. 2 is an inverted plan view. Fig. 3 is a sectional view on an enlarged scale showing a detail of construction.

In the particular drawings selected for more fully disclosing my invention, 1 represents a conical body of any suitable material having its lower edge turned inwardly and preferably, as shown in the present instance, this is accomplished by providing the lower edge with a bead 1'. A second conical body 3 having its upper edge turned outwardly, as for example by beading it as shown at 3', is detachably secured to the body 1 by forcing it up into the latter against the downturned edge 5 of the elastic diaphragm 4, preferably of pure rubber, so that said downturned edge, which preferably is thicker than the diaphragm

itself, is compressed between the beaded edges of the conical bodies 1 and 3, respectively. In this way an absolutely watertight joint is formed between the diaphragm and the conical bodies and at the same time the body 3 may conveniently be separated from the body 1, either for the purpose of renewing the diaphragm or inserting into the body 1 a larger conical body as indicated by dotted lines in Fig. 1.

The upper portion of the conical body 1 terminates in a tube 2, to which may be secured by soldering or otherwise, a sleeve 6, the upper end of which is provided with a flange 7. A hollow handle 8, the lower portion of which is provided with perforations 9, is disposed within said sleeve and the

lower end thereof is secured to the diaphragm by means of the screw 12 which passes through the washer 11 and the diaphragm, and is threaded into the plug 10 attached to the lower end of the handle. It will be understood of course that any suitable means may be employed for attaching the handle to the diaphragm so as to make a water-tight joint between them. A spiral spring 14, interposed between the flange 7 and the collar 13, which is fixed to the handle, maintains the diaphragm flexed upwardly in the position shown in Fig. 1.

On the downstroke of the clothes pounder, air and water will be forced through the clothes and at the end of the downstroke or shortly before, the further movement of the handle with respect to the conical body 1 against the tension of the spring 14 will flex the diaphragm downwardly, thereby forcing an additional amount of air and water through the clothes. On the upstroke the suction created will be increased by the reaction of the diaphragm and spring, the air in the body 1 above the diaphragm escaping through the hollow handle by way of the perforations 9, so that there will be no interference with the free action of the diaphragm on account of compression of the air above the same.

I claim:

1. A clothes-pounder comprising a conical body having a beaded lower edge, a second conical body having a beaded upper edge, an elastic diaphragm extending across the first mentioned conical body and having its outer edge compressed between the beaded edges of said conical bodies, and a hollow handle secured to said diaphragm.

2. A clothes-pounder comprising a conical body having a beaded lower edge, a second conical body having a beaded upper edge, an elastic diaphragm extending across the first mentioned conical body and having its outer edge compressed between the beaded edges of said conical bodies, and a hollow handle secured to said diaphragm and resilient means for maintaining said diaphragm flexed upwardly.

3. A clothes-pounder comprising two conical bodies, and an elastic diaphragm, the outer edge of which is compressed between said conical bodies.

4. A clothes-pounder comprising two conical bodies and an elastic diaphragm extending across the same.

5. A clothes-pounder comprising two conical bodies and an elastic diaphragm extending across the same, said diaphragm having a thickened outer edge and said outer edge being compressed between said conical bodies.

In testimony whereof, I have hereunto

subscribed my name this 17th day of October, 1913.

NILS FREDERICK AMBURSEN.
